[57] CLAIM

The ornamental design for a handpiece for manicure machine, substantially as shown and described.

DESCRIPTION

FIG. 1 is a perspective view of a handpiece for manicure machine showing my new design;
FIG. 2 is a side elevational view thereof;
FIG. 3 is a front elevational view thereof;
FIG. 4 is a rear elevational view thereof;
FIG. 5 is a perspective view of a modified embodiment of the design shown in FIGS. 1 through 4;
FIG. 6 is a side elevational view thereof;
FIG. 7 is a front elevational view thereof; and
FIG. 8 is a rear elevational view thereof.
